(57) **CLAIM**

The ornamental design for a nozzle for dishwasher, as shown and described.

DESCRIPTION

FIG. 1 is a front perspective view of the nozzle for dishwasher showing our new design;

FIG. 2 is a front view thereof;

FIG. 3 is a back view thereof;

FIG. 4 is a left side view thereof;

FIG. 5 is a right side view thereof;

FIG. 6 is a top plan view thereof;

FIG. 7 is a bottom plan view thereof; and,

FIG. 8 is a perspective view showing the design in state of use that the claimed design has been installed at bottom inside of a dishwasher.

The broken lines depict portions of the nozzle for dishwasher that form no part of the claimed design. The portions

(Continued)

of FIG. 8 drawn in broken lines show environmental structure only and form no part of the claimed design.

1 Claim, 8 Drawing Sheets
